ABSTRACT OF THE DISCLOSURE

Pipe is laid in deep water by unreeling a continuous length of pipe from a reel on water bottom in which a free end of the pipe is attached to a selected location and the reel is moved away from the selected location such as by towing from water surface.

BACKGROUND OF THE INVENTION

Field of the invention

The present invention is directed to laying pipe in deep water. More particularly, the invention is concerned with laying pipe in deep water from a reel. In its more specific aspects, the invention is concerned with laying pipe in deep water from a reel while avoiding tension and bending stress.

Description of the prior art

Offshore pipe lines are conveniently laid from floating vessels or barges; the pipe may be connected by joint and lowered progressively to ocean floor as the lay vessel moves forward and the pipe may be unspooled from a continuous reel of pipe, and pipe up to 8" in diameter has been spooled.

The problem with either technique while laying pipe in deep water is the tendency of the pipe to buckle due to its own unsupported weight at the point where it leaves the stern of the lay barge. This problem has been coped with in the prior art by use of long stingers or chutes at the stern of the barge or at the side of the barge to minimize the angle of departure and the resulting pipe stress. Buoyant chambers have also been used to support the pipe between the barge and the ocean floor. With respect to laying pipe from pipe reels spool tension has been maintained on the pipe as it is unreeled to reduce the bending stress to an acceptable level; tension may be maintained by winch and anchor systems off the bow of the barge.

As water depth increases the amount of the unsupported pipe between the barge and water bottom increases, thus increasing bending stress. Laying pipe in water as deep as 1000 feet or more provides substantial bending stresses which must be offset by use of longer stingers, more buoyancy and increasing pipe tension. However, the practical size of stingers or chutes is exceeded when they become too large and cumbersome and the available tension is limited by anchor holding capabilities. The foregoing problems effectively limit the water depth of current pipe laying methods. In accordance with the present invention, the problems are substantially eliminated or avoided.

Specific prior art considered with respect to this invention include the following listed U.S. Pats.: Re. 20,665, 2,142,135, 3,022,633, 3,140,745, 3,230,721, 3,256,695.

SUMMARY OF THE INVENTION

The present invention may be briefly described and summarized as a method of laying pipe in deep water in which a reel of pipe having a free end is supported on and/or adjacent water bottom. The free end of the pipe is attached to a selected location which may be an underwater wellhead anchor pipe or pile, platform or

2

any other desirable or selected location. The reel is then moved on water bottom away from the selected location thereby unreeling the pipe and laying it on water bottom. This pipe laying technique reduces bending stress in the pipe to a minimum and is insensitive to water depth.

5 The spooled pipe is unreeled from a submerged position on or adjacent to or near the water bottom and thus the only tension required is that necessary to unreel and straighten the pipe. The reel may be moved on water bottom by towing it from water surface. The reel may be supported on or adjacent water bottom by providing controlled buoyancy such that the reel is maintained adjacent water bottom; or the reel may be mounted or supported on a frame member to which a towing cable or line is attached which extends to a powered vessel at water surface. As the pipe is unreeled it may connect the selected location to an accessible location which may be a platform or vessel in the water or it may extend to the shore.

The present invention may also be briefly summarized as involving apparatus comprising a supporting member adapted to be moved on or adjacent water bottom having a pipe reel mounted thereon and a continuous length of the pipe reeled on the pipe reel with the continuous length of the pipe having a free end adapted to be connected to a selected location. Means are provided for moving the supported member along water bottom.

The apparatus also comprises straightening means for straightening the pipe as it is unreeled and may include buoyancy means which may be adjustable or at least a portion thereof releasable.

BRIEF DESCRIPTION OF THE DRAWING

The present invention will be further described and illustrated by reference to the drawings in which:

35 FIG. 1 illustrates one embodiment of the present invention; and

FIG. 2 illustrates another embodiment.

DESCRIPTION OF THE PREFERRED MODE AND EMBODIMENT

40 Referring now to the drawings and particularly to FIG. 1, numeral 11 designates a body of water having surface 12 and a water bottom 13; floating on the surface 12 is a powered vessel 14 such as a tug and arranged on or adjacent water bottom is a pipe reel 15 containing a continuous length of pipe reeled thereon, the free end 16 of which is attached to a wellhead 17 on water bottom 13. The pipe reel is mounted on a center axle 18 which in turn is surrounded by a spaced wall member 19 which defines a buoyant chamber 20. The wall member 19 forms the reel 15 on which the pipe is reeled. The buoyant chamber 20 together with releasable buoyancy means 21 which may be attached to the pipe reel 15 by flexible member 22 such as a cable, line, chain, or tubular member provides only sufficient buoyancy to maintain the pipe reel 15 at or adjacent water bottom 13. Connected to the pipe reel 15 by frame member 23 are pairs of straightening wheels 14 between which the pipe travels as it is unspooled from the reel 15. The reel 15 may be connected to the vessel 14 by a tow cable 25 which causes the pipe to unreel in the direction indicated by the arrows. Alternately and perhaps preferably, as shown in FIG. 2, the reel 15 may be mounted on a frame member 26 which in turn is supported by a supporting member or skid frame member 27 to which is attached tow cable 25a by means 28 and which likewise extends to and is connected with powered vessel 14.

45 As the powered vessel 14 moves in the direction of the arrows, the pipe is unreeled from the reel 15 and is laid on water 13 avoiding the problems of the prior art. Rather than employing a powered vessel at the water surface 12, a submarine may be used or the reel 15 or the

frame 27 may be provided with power or propelling means for moving the reel along water bottom.

Thus, in accordance with the present invention, a method and apparatus are provided employing a submersible pipe reel or drum having integral buoyancy and releasable or adjustable buoyancy. In operation the reel rotates around a center shaft or axle 18 and the whole assembly may be free or mounted on a frame; where the assembly is free, the skid frame member 27 and frame 26 would be omitted. The pipe is originally spooled on the reel and the reel contains a buoyant chamber 20 and the buoyant chamber 20 may be included in or attached to skid frame 27. The buoyancy is slightly less than the weight of the reel and skid assembly less the weight of the pipe. Attached to the center axle and skid frame is a set of straightening wheels to remove the curvature from the pipe. Also as shown in the drawing, attached to the center axle and skid frame is at least one and preferably a plurality of releasable buoyant chambers 21 providing buoyancy equal to the weight of the spool pipe. Alternatively, a controlled buoyant chamber may be provided permitting selective floating or releasing to vary the buoyancy of the buoyant chamber 20, thereby omitting buoyancy means 21. Thus, the entire assembly has a slightly negative buoyancy.

In laying pipe using the present invention, the spool with the spooled pipe on it is moved to the work site by barge or it may be floated to the work site. The reel assembly is then lowered or submerged with tow lines attached near the starting point which may be a platform, a vessel, an underwater well, or an anchor pipe, piling, and the like. The free end of the pipe is attached to the starting point or selected location using divers or remote connecting means. The towed vessel is then moved away from the selected location in the desired direction towing the cable to unreel and straighten the pipe as the drum or reel rotates around the axle. Depending on the ratio of the spooled pipe to reel assembly weight releasable buoyancy representing preselected fractions of the pipe weight is released at various intervals to compensate for the pipe weight unreeled. On reaching the end of the length of the pipe, the reel assembly may be recovered by a hoisting mechanism attached to the buoyancy chamber. The procedure may be repeated as desired or necessary until the pipe is brought to an accessible location which may be a vessel, a platform or the shore or any other location accessible from water surface or land.

Thus, the present invention provides new and unobvious results and eliminates problems which have plagued the industry in laying pipe in deep water from 100 to 5000 feet. Of course, the invention is not to be limited to any particular water depth and it may be applied in waters of greater or lesser depths than those given.

The invention is, therefore, of considerable advantage and utility.

The nature and objects of the present invention having been completely described and illustrated and the best mode and embodiment contemplated set forth what I wish to claim as new and useful and secure by Letters Patent is:

1. A method for laying pipe in deep water which comprises:

supporting a submerged reel of pipe having a free end on water bottom;
attaching said free end to a selected location on water bottom; and
moving said reel on said water bottom away from said selected location and thereby unreeling said pipe and laying it on said water bottom.

2. A method in accordance with claim 1 in which the reel is moved on water bottom by towing it from water surface.

3. A method in accordance with claim 1 in which the selected location is a wellhead on water bottom.

4. A method in accordance with claim 1 in which the pipe is straightened as it is unreeled.

5. A method in accordance with claim 1 in which the unreeled pipe connects the selected location with an accessible location.

6. A method in accordance with claim 5 in which the accessible location is at least adjacent water surface.

7. A method in accordance with claim 1 in which:

- (a) the reel is moved on water bottom by towing it from water surface;
- (b) the selected location is a wellhead on water bottom; and
- (c) the pipe is straightened as it is unreeled.

8. A method in accordance with claim 7 in which the unreeled pipe connects the selected location with a location accessible from water surface.

9. A method in accordance with claim 7 in which the unreeled pipe connects to an accessible location on land.

10. A method in accordance with claim 1 in which the reel is buoyantly supported.

11. Apparatus for laying pipe on water bottom which comprises:

a supporting member on water bottom;
buoyancy means on said supporting member;
means for adjusting the buoyancy of said buoyancy means;
a pipe reel having a continuous length of pipe reeled thereon and mounted on said supporting member, said pipe having a free end adapted to be connected to a selected location on water bottom; and
means attached to said supporting member for moving said supporting member along water bottom.

12. Apparatus in accordance with claim 11 in which means arranged adjacent said reel is provided for straightening said pipe as it is unreeled.

13. Apparatus in accordance with claim 11 in which said apparatus is provided with coaxial buoyancy means.

14. Apparatus in accordance with claim 1 in which the moving means comprises a flexible means extending from said supporting means to a powered vessel on water surface.

15. Apparatus in accordance with claim 11 in which the supporting means is coaxial with the reel.

16. Apparatus in accordance with claim 11 in which the supporting means comprises a skid member.

17. Apparatus in accordance with claim 11 in which the buoyancy means comprises a plurality of releasable buoyancy means.

18. Apparatus for laying pipe on water bottom which comprises:

a pipe reel provided with a coaxial axle;
wall means forming a buoyant chamber mounted between said reel and axle;
a continuous length of pipe having a free end arranged on said reel;
releasable buoyancy means attached to said reel; and
means for moving said reel along water bottom.
